UNITED STATES PATENT OFFICE.

BENJAMIN F. FAUNCE, OF WESTMONT BOROUGH, PENNSYLVANIA.

MANIPULATOR.

Application filed April 29, 1922. Serial No. 557,245.

To all whom it may concern:

Be it known that I, BENJAMIN F. FAUNCE, a citizen of the United States, and a resident of the borough of Westmont, county of Cambria, and State of Pennsylvania, have invented certain new and useful Improvements in Manipulators; and I do hereby declare the following to be a full, clear, and exact description of the invention, such as will enable others skilled in the art to which it appertains to make and use the same.

My invention relates generally to a manipulator which is adapted for use in handling hot metal in solid form to and when in a mill and thence elsewhere, and is particularly adapted for handling heated steel wheel blanks to and in a mill, and after they have been operated upon in said mill the rolled blanks or wheels may then be further handled by the manipulator and placed elsewhere as desired.

A wheel blank is preferably heated in a furnace where it lies flat and it may be withdrawn therefrom by any suitable means and placed with its central perforation over a mandrel carried by one arm of the manipulator, and after this is done a swinging arm is closed down to hold the other end of the mandrel and the manipulator is then traversed towards the rolling mill and the wheel or blank turned from its flat or horizontal position into a substantially vertical position, and thence by means of my apparatus is placed in the mill and held against the forming rolls thereof and rolled or formed while rotating with or on the mandrel of the manipulator. After this is done the wheel or blank is withdrawn from the mill and placed elsewhere by the manipulator and the apparatus is then ready for a repetition of the operation.

My manipulator holds the blank in a mandrel inserted in the central perforation thereof, and in addition to handling the blank into and out of the mill it also serves another very useful purpose in holding it in the mill while the rolling operation proceeds, and this obviates the necessity of any other and prior customary means of holding blanks in the mill. My apparatus therefore serves various purposes and consequently facilitates the operation of forming wheels and similar annular bodies.

The arms which carry the mandrel may fit the ends of the same tightly so that the

mandrel will not turn, but preferably the arms are provided with bushings or bearings for the ends of the mandrel in which it may rotate, and this thereby prevents unnecessary rotation of the hot blank on the mandrel, which might distort it.

In order to guide the apparatus during rolling in the wheel mill, the manipulator arms which carry the blank are guided on the head-blocks of the mill during the rolling process, so that the blank will be accurately presented to the rolls of the mill for proper operation, and these head-blocks may be adjusted in various directions by liners or otherwise to suit the work to be done. As, during the process of rolling the wheel blank becomes larger, its axis necessarily recedes from the back or tread roll, which therefore necessitates the retreat of the manipulator, which occurs automatically, as the apparatus is mounted on a wheeled truck and may readily retreat from or advance to the mill as necessary. After the wheel is rolled, while being rotatably held by the manipulator, and is still hot, it is taken to the coning press for shaping the web into the usual standard form, and as the coning press operates when the wheel is in a horizontal plane my manipulator turns the wheel into that position before delivery to the coning press or to the carrier which delivers it thereto.

My manipulator facilitates production and also obviates the hot and laborious work of inserting a mandrel into the wheel perforation by hand, and it also avoids the necessity of placing the mandrel caps or bearings on the mandrel by hand as previously customary.

In addition to this the wheel or blank handled by my manipulator will be free from injury or indentations caused by the prior necessary gripping of power charging machines or other unnecessary handling by other methods, and the rolled wheel will also be preserved from the deformations or indentations caused by bumping the same against parts of the mill or housings when it is withdrawn by the methods previously customary.

Having thus given a general description of my invention, I will now, in order to make the matter more clear, refer to the annexed two sheets of drawings, which form part of this specification, and in which like characters refer to like parts.

Figure 1 is a top plan view of my manipulator and a portion of a wheel mill to show the application of my invention; Figure 2 is a side elevation with a portion of the 5 wheel mill in dotted lines; Figure 3 is a rear end elevation; Figure 4 is a side elevation of my manipulator similar to Figure 2, but showing the wheel clamping arms or tongs rotated a quarter of a revolution with the 10 pivoted swing arm raised and the wheel blank in position on the receiving arm; Figure 5 is a longitudinal sectional plan through my manipulator taken on the line V—V of Figure 4; Figure 6 is a front elevation of a 15 portion of the supporting frame of my machine; Figure 7 is a detail sectional elevation, on a larger scale, of the end of one of the receiving arms taken on the line VII—VII of Figure 8, and Figure 8 is a detail 20 tail sectional elevation also drawn on a larger scale through the end of the receiving arms, mandrel and central portion of the wheel or blank.

Referring now to the characters of reference on the drawings:—1 is the base plate 25 of the manipulator, 2 is the upper supporting frame thereof which is mounted on the base plate as shown, 3 are the track wheels, the axles of which are journaled in the supporting frame 2. A large journal bearing 30 4 is provided in the upper part of the apparatus to receive the rotatable shaft 5, which shaft is provided with a reduced rear end portion 6. A supporting fork 7 is 35 mounted on and keyed to the shaft 6 and is provided with smaller journal bearings 8 in its end portions, in which the cylinder 9 is mounted by means of its trunnions 10 so that it can swing slightly therein. Fluid pressure connections 11 connect fluid under pressure to the cylinder 9 and these are joined to 40 a control valve and to any suitable source of fluid under pressure, whereby the piston of the cylinder may be moved backward and forward and the piston rod will be moved 45 correspondingly. The piston rod 12 is pivoted at its outer end 13 to the swinging arm 14 as shown, and this arm is therefore adapted to swing to an open position as illustrated in 50 Figure 4, or to a closed position as shown in Figure 1 with respect to the other arm 49. The pivot bolt on which it swings is 55 15 and this passes through holes in the ears 16 of the integral laterally extending portions 60 of the shaft 5, which shaft also has the longitudinally projecting arm 49 extending integrally therefrom. The arm 49 is mounted and secured on or made as an integral part of the shaft 5, and this arm and shaft are 65 adapted to be rotated as will be hereinafter described, and while this is done the swinging arm 14 will revolve about the same axis. Cylindrical openings 17 are provided in the ends of the arms 14 and 70 49 in which are mounted the bushings 18 75 provided with central openings 19 adapted to receive the ends of the mandrel and allow the same to rotate therein, these bushings being provided with flanged ends 20 as illustrated, and are secured to the ends 70 of the arms by the bolts 21. The mandrel 22 is provided with a central portion, which may be made of any size to correspond with the size of the opening or perforation in the wheel hub, and this mandrel is provided 75 with reduced end portions 23 and 23' which are journaled in the bushings 18 as illustrated. A wheel or blank 24 is shown mounted on the mandrel which latter projects through the central opening thereof 80 and preferably with a slight amount of clearance to facilitate its introduction and withdrawal. Attached to or forming part of the frame is a socket or journal bearing 25 adapted to receive the cylindrical portion 85 or shaft 5 of the rotatable arm 49, and 26 are adjusting bolts adapted to adjust and limit the rotation of said arm.

Part of the shaft 5 is cylindrical as shown, but it has integrally formed with it the laterally extending portions which have the ears or projections 16 and these each have their outer surfaces tangent to the semi-cylindrical portion of the shaft and are flat as shown, so that as the shaft rotates one of 90 flat portions referred to contacts with the end of the bolt 26 to limit the rotation of the shaft and the amount of rotation may be slightly adjusted by screwing the bolt 26 in or out. A cylinder 27 is provided for rotating the arm 49 in one direction and another cylinder 28 for rotating it in reverse direction. A connecting plunger 29 operates with its opposite ends in these cylinders, the plunger being provided with a groove or 95 slide-way 30 adapted to receive the roller 31 mounted on the stub shaft 32, which shaft is mounted in the fork 7 with its axis eccentric with respect to the axis of rotation of the shaft 5 and the arm 49, and it thereby operates as a crank pin. As the plunger 29 is moved backward or forward in the cylinders 27 and 28 the shaft 5 is turned thereby and this rotates the arm 49 and also revolves the arm 14 about the same axis. The cylinders 100 27 and 28 are provided with pipe connections 33, which may be provided with any suitable control valve and source of fluid under pressure. 34 is the rear axle of the apparatus provided with a gear 35 mounted thereon, 36 is a pinion mounted on the shaft 37 adapted to mesh with the gear 35 and 38 is a gear on the other end of said shaft adapted to mesh with the pinion 39 mounted on the end of the shaft 40, which latter is 105 mounted in the bearings 41 and provided with a gear 42, which meshes with the pinion 43 mounted on the motor shaft 44 of the electric motor 45. This apparatus is thereby adapted to traverse the manipulator back- 110 115 120 125 130

ward or forward on its track rails as illustrated.

As illustrated in full lines in Figure 1 and by dotted lines in Figure 2, 46 is the tread roll of the wheel mill, 47 are the web rolls thereof and 48 is a portion of the framework of the mill.

As viewed particularly in Figures 1 and 2, the ends of the arms 14 and 49 are adapted to rest between the head-blocks of the mill in order to properly maintain the position of the blank or wheel during the rolling, and as the blank increases in diameter the arms 14 and 49, which carry the mandrel mounted near their ends, may be automatically or otherwise retracted while slidably resting between said head blocks or between the liners thereof.

The head-blocks of the mill, as illustrated in dotted lines in Figure 2, are provided with a bottom liner 51 and a top liner 52, which are seated on and secured to the head-blocks of the mill frame, and these may be of any thicknesses to suit the work to be done, and their distance apart is slightly greater than the thicknesses of the ends of the arms 14 and 49, which are inserted between them. I prefer to arrange the arms so that when the mill is running and the wheel is being rolled, the ends of the arms will contact with the upper liner 52 to hold the wheel in position, as during its rotation the wheel when being rolled has a tendency to lift upwardly, and this is resisted by contact with the top liner 52 with the ends of the arms 14 and 49. When rolling, the wheel preferably turns in an anti-clockwise direction as viewed in Figure 2, while the tread roll rotates in a clockwise direction.

In order to slightly adjust the heights of the arms 14 and 49, I provide adjusting screws 50, whereby the supports of the machine and the arms may be raised or lowered with respect to the forward wheels 3 and the track, and this will also allow for any minor vertical adjustments required in the arms 14 and 49 and the mandrel 22 which they carry to suit the work to be done.

It should be noted that the arm 14 may be moved to closed or open position with relation to the other arm 49, and it may hold or release one end of the mandrel, and both it and the other arm 49 when closed may be turned around an axis extending in the general direction of their lengths in order to partially rotate the wheel blank from a substantially horizontal to a generally vertical position, and vice-versa.

The operation of my apparatus is as follows:—A hot wheel blank ready for rolling in the wheel mill may be placed on the mandrel 22 by a furnace drawing machine or otherwise, when the arms are in the position illustrated in Figure 4, whereupon the arm 14 is caused to swing by admission of fluid

to the rear pipe 11, thereby swinging this arm and thus placing its bushing 18 over one of the reduced ends 23 of the mandrel. Fluid under pressure is then admitted to the cylinder 28 and the other fluid allowed to escape from the cylinder 27, which rotates the shaft 5 and the arm 49 and the arm 14 also revolves around the axis of the shaft 5, and while the blank assumes an upright or approximately vertical position the motor 45 is started in the proper direction, traverses the manipulator on its track, and places the wheel in the wheel mill against the tread roll 46 while the web rolls are in open position. The web rolls are then projected against it while rotating, and the various rolls then roll the blank while it is being held by the manipulator, and as this is done the wheel blank increases in diameter and the apparatus gradually and automatically retracts from the mill to accommodate this increase in diameter. After the rolling is finished the web rolls 47 are opened, the motor 45 rotated in reverse direction and the wheel blank withdrawn from the mill, whereupon the movement of the plunger 29 in a reverse direction is accomplished by the action of the cylinders 28 and 27, the wheel thereby turned to horizontal position, and the arm 14 is swung to open position by the reverse action of the cylinder 9 and the wheel is delivered to a carrier, which delivers it to the coning press or elsewhere for finishing or otherwise.

Although I have shown and described my invention in considerable detail, I do not wish to be limited to the exact and specific details thereof, as shown and described, but may use such modifications in, substitutions for, or equivalents thereof as are embraced within the scope of my invention, or as pointed out in the claims.

Having thus described my invention, what I claim and desire to secure by Letters Patent is:—

1. In a manipulator, a pair of arms, means for relatively opening and closing the same, means for turning them on an axis extending in the general direction of their lengths when closed, and means mounted near the ends of said arms for rotatably holding a blank.

2. A manipulator, mounted on a carriage adapted to be moved backward or forward, a rotatable arm mounted on said carriage, a swinging arm pivotally connected with said rotating arm, means for swinging said latter arm and for simultaneously turning both of said arms, said arms being provided near their outer ends with means for rotatably holding a blank.

3. A manipulator, mounted on a carriage adapted to be moved backward or forward, a rotatable arm mounted on said carriage, a swinging arm pivotally connected with said

- rotating arm, means for swinging said latter arm and for simultaneously turning both of said arms, said arms being provided near their outer ends with means for rotatably holding a blank. 5. A manipulator, mounted on a carriage adapted to be moved backward and forward, a rotatable arm mounted on said carriage, a swinging arm pivotally connected with 10 said rotating arm, means for swinging said latter arm and for simultaneously turning both of said arms, said arms being provided at their outer ends with a mandrel adapted to rotatably hold a blank. 15. In a manipulator, a pair of arms, means for turning the same about an axis extending in the general direction of their lengths when closed, means for relatively opening and closing said arms, and a mandrel mounted in the outer ends of said arms. 20. In a manipulator, a pair of arms, means for turning the same about an axis extending in the general direction of their lengths when closed, means for relatively opening and closing said arms, and a mandrel rotatably mounted in bearings near the outer ends of said arms. 25. In a manipulator, comprising a carriage, means for moving the same backward or forward, an arm rotatably mounted on said carriage, a swinging arm pivoted thereto, openings in the ends of said arms, and a mandrel rotatably mounted in said openings. 30. A manipulator, comprising a carriage, means for moving the same backward or forward, an arm rotatably mounted on said carriage, a swinging arm pivoted thereto, openings in the ends of said arms, and a mandrel rotatably mounted in said openings. 35. A manipulator, comprising a carriage, means for moving the same backward or forward, an arm rotatably mounted on said carriage, a swinging arm pivoted thereto, openings in the ends of said arms, a mandrel rotatably mounted in said openings, and means for simultaneously turning said arms. 40. A manipulator, comprising a carriage, means for moving same backward or forward, an arm rotatably mounted in said carriage, a swinging arm pivoted thereto, said rotatable arm being provided with a shaft, a yoke secured to said shaft and provided with a crank pin eccentrically located with respect thereto, a pressure plunger adapted to partially rotate said shaft by said crank pin, openings in the ends of said arms, and a mandrel adapted to be rotatably mounted therein. 45. In a manipulator, a carriage, a pair of arms mounted thereon, and pivotally connected to each other, means for relatively opening or closing said arms, and for turning them around an axis extending in the general direction of their lengths when closed and a mandrel rotatably mounted near the ends of said arms. 50. In a manipulator, a carriage, a pair of arms mounted thereon and pivotally connected to each other, means for relatively opening and closing said arms, openings in 55 the ends of said arms, a mandrel rotatably mounted in said openings, and means for turning said arms around an axis extending in the general direction of their lengths when closed. 60. In a manipulator, a carriage, means for moving said carriage backward and forward, a pair of arms mounted thereon and pivotally connected to each other, means for relatively opening or closing said arms, perforations in the ends of said arms, a mandrel rotatably mounted in said perforations adapted to receive and hold a wheel blank thereon between said arms, and means for turning said arms around an axis extending in the general direction of their lengths. 65. The combination with a wheel mill, of a manipulator provided with a pair of arms pivotally connected to be relatively opened and closed, a mandrel rotatably mounted near the ends of said arms, adapted to receive a wheel blank provided with a central perforation, and head-block guides on said mill adapted to hold said arms in position desired. 70. The combination with a wheel mill, of a manipulator provided with a pair of arms adapted to be relatively opened and closed, a mandrel rotatably mounted near the ends of said arms, adapted to hold a wheel blank provided with a central perforation, and head-block guides on said mill adapted to hold said arms in position desired. 75. The combination with a wheel mill, of a manipulator provided with a pair of arms pivotally connected to be relatively opened and closed, a mandrel rotatably mounted near the ends of said arms, adapted to receive a wheel blank provided with a central perforation, and head-block guides on said mill adapted to hold said arms in position desired. 80. The combination with a wheel mill, of a manipulator provided with a pair of arms adapted to be relatively opened and closed, a mandrel rotatably mounted near the ends of said arms, adapted to hold a wheel blank provided with a central perforation, and head-block guides on said mill adapted to hold said arms in position desired. 85. The combination with a wheel mill, of a manipulator provided with a pair of arms adapted to be relatively opened and closed, a mandrel rotatably mounted near the ends of said arms, adapted to receive a wheel blank provided with a central perforation, and head-block guides on said mill adapted to hold said arms in position desired. 90. The combination with a wheel mill, of a manipulator provided with a pair of arms adapted to be relatively opened and closed, a mandrel rotatably mounted near the ends of said arms, adapted to hold a wheel blank provided with a central perforation, and head-block guides on said mill adapted to hold said arms in position desired. 95. The combination with a wheel mill, of a manipulator provided with a pair of arms adapted to be relatively opened and closed, a mandrel rotatably mounted near the ends of said arms, adapted to receive a wheel blank provided with a central perforation, and head-block guides on said mill adapted to hold said arms in position desired. 100. The combination with a wheel mill, of a manipulator provided with a pair of arms adapted to be relatively opened and closed, a mandrel rotatably mounted near the ends of said arms, adapted to hold a wheel blank provided with a central perforation, and head-block guides on said mill adapted to hold said arms in position desired. 105. The combination with a wheel mill, of a manipulator provided with a pair of arms adapted to be relatively opened and closed, a mandrel rotatably mounted in the ends of said arms, adapted to hold a wheel blank mounted with its central perforation over said mandrel, head-blocks on said mill provided with liners of suitable thicknesses adapted to hold and guide the ends of said arms during the rolling of the blank. 110. The combination with a wheel mill, of a manipulator provided with a pair of arms adapted to be relatively opened and closed, a mandrel rotatably mounted in the ends of said arms, adapted to hold a wheel blank, head-blocks on said mill provided with liners of suitable thicknesses adapted to hold and guide the ends of said arms at the level desired during the rolling of the blank, means for advancing said arms, and for permitting the automatic retraction thereof as the blank increases in diameter. 115. In witness whereof I hereunto affix my signature. 120. BENJAMIN F. FAUNCE. 125.
